UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,244,264.

Specification of Letters Patent. Patented Oct. 23, 1917.

Application filed June 12, 1916. Serial No. 103,250.

To all whom it may concern:

Be it known that I, HENRY G. VOIGHT, a citizen of the United States, residing in New Britain, county of Hartford, and State 5 of Connecticut, have invented certain new and useful Improvements in Locks, of which the following is a full, clear, and exact description.

This invention relates to locks and has 10 special reference to locks for hotel rooms.

The invention refers particularly to locks of what I call the one-bolt type, viz., those where a single dead bolt is employed which is protractable from either side of the door, 15 provision being made for blocking the operation of certain keys at the outside of the door when the bolt has been shot from the inside, although permitting the withdrawal of the bolt from the outside at all times by 20 a special key. My improvements are also applicable to a lock in which a latch bolt is retractable by all of the keys when the dead bolt is in the retracted position, said latch bolt, however, being retracted only by the 25 emergency key when the dead bolt is in the protracted position.

One of the primary objects of the invention is to provide a lock in which a cylinder having a rollback or cam arm radially 30 movable on the key plug is adapted to operate two different members by means of said rollback or cam arm when said cylinder is actuated by one key, whereas said rollback or cam arm is operative on only one of said 35 members when another key is used. By this arrangement, one roll back or cam arm is adapted to do the work which in many cases has been done by two roll backs or cam arms, and the construction and operation of 40 the lock are therefore simplified.

Another object of the invention is to improve the general construction of locks of the class to which the invention relates.

To these and other ends, the invention 45 consists in the novel features and combinations of parts to be hereinafter described and claimed.

In the accompanying drawings,

Figure 1 is a front elevation of a mortise 50 lock embodying my improvements, with the cap plate removed, the parts being in the normal position;

Fig. 2 is a view of the upper part of the lock, showing the latch bolt retracted 55 by means of the change key;

Fig. 3 shows the upper part of the lock, with the roll back turned by the emergency key to protract the bolt;

Fig. 4 is a section on line 4—4 of Fig. 1, showing the change key inserted into the 60 cylinder;

Fig. 5 is a similar view, showing the emergency key inserted into the cylinder;

Fig. 6 is a detail longitudinal section of a portion of the cylinder, showing the radially movable roll back mounted on the key 65 plug;

Fig. 7 is an end view of the cylinder, with the roll back detached; and

Fig. 8 is a detail face view of the roll 70 back detached.

In the embodiment illustrated, the case 10 of the lock is provided with the usual latch bolt 11 adapted to be retracted by a knob shoe 12, coöperating with the usual 75 inside and outside hubs 13, 14. Above the latch bolt 11 is mounted a dead bolt 15 adapted to protrude through the face plate 15^a. This dead bolt has pivoted thereto a tumbler 16, with a loop 17 and a projection 18 on the loop extending between talons 19 on the lower part of the dead bolt, and adapted to be engaged by the wing 20 of a thumb turn hub 21. The arrangement is such that the dead bolt may be protracted 85 by rotating the thumb turn hub in a clockwise direction with respect to Fig. 1. The projection 18 on the tumbler loop is at the lower part of the loop, and at the upper part thereof is a similar projection 22 extending 90 between talons 23 on the upper part of the bolt. The tumbler 16 is provided with a lug 24 coöperating with a racking post or fence 25 on the back of the case, whereby the bolt is locked in the advanced position or the retracted position. 95

A cylinder lock 26 is secured in an opening in the lock case at the outside of the door, and is adapted to be operated by a plurality of keys, including a guest or 100 change key 27 (Fig. 4), and an emergency key 28 (Fig. 5). This cylinder lock is provided with a roll back or cam arm 29 which is rotatable in a single plane only, which plane is the plane of the talons 23 of the 105 dead bolt. The roll back is adapted to enter between the talons 23 and engage the projection 22 of the tumbler for the purpose of actuating the bolt 15. The roll back is also adapted to retract the latch bolt 11 when 110

the dead bolt is in the retracted position. For this purpose, the dead bolt carries a latch retracting lever 30, pivoted on said bolt at 31, and having a free end 32 adapted to rest on the upper edge of a main latch retracting lever 33, pivoted in the case at 34. This latch retracting lever 33 has a downwardly extending arm 35, co-operating with a cross head 36 on the latch bolt stem 10 in the usual manner. The latch bolt may be retracted when the dead bolt is in the retracted position by turning the roll back 29 into contact with the free end of lever 30, which thereby actuates the main latch retracting lever 33, as shown in Fig. 2. In operating the lever 30, the roll back 29 abuts a projection on the end portion 32 of lever 30, which projection is in the plane of the talons 23 and of the roll back.

20 The cylinder lock 26 in the example shown has the usual case 38 and face plate or escutcheon 39. A key plug 40 is rotatable in the case 38 and is controlled by the usual pin tumblers 41. The roll back 29 previously mentioned is carried by the rear end portion of the key plug 40, but is radially movable thereon. The rear end portion of the key plug is reduced so as to present an extension 42 of generally rectangular cross-section, as shown in Fig. 7. Over this reduced extension 42 and against a shoulder 43 on the main part of the key plug is fitted a member 44 in the shape of a disk which is provided with small perforations 45 registering with screw openings in the key plug. The roll back 29 is of more or less usual configuration, but instead of being fixed against movement on the key plug, it is mounted to slide on the extension 42. For this purpose, the front or forward face of the roll back 29 is provided with a guide groove 46 engaging the extension 42, and at the sides of the groove 46 are vertically directed slots 47 which provide clearance for small screws 48, by means of which the roll back is secured to the key plug. Each of these screws 48 passes through one of the slots 47, thence through one of the openings 45 in the member 44, and then 45 engages the threads of tapped opening or socket in the key plug itself. By providing the slots 47, the roll back 29 is permitted to move radially relatively to the key plug on the extension 42 from the position shown in 50 Fig. 1 to that shown in Fig. 3. This roll back, however, is normally held in the position shown in Fig. 1 relatively to the key plug by means of a small spring 49, which is connected at one end to a projection 50 on the member 44, and at the other end to a pin 51 on the outer part of the roll back arm. This spring 49 is accommodated in a suitable socket 52 on the forward or front face of the roll back, as shown in Figs. 6 55 and 8. The spring 49 normally holds the

roll back in the position shown in Fig. 6, with the upper ends of the slots 47 in abutment with the shanks of the screws 48. The roll back is provided with a notch 53 at its lower part, which notch enters the same 70 from the bottom, and is located in the back wall of the guide groove 46. The notch does not extend as high as the top of the keyway 54, and its upper edge 55 presents an abutment adapted to be engaged by the 75 emergency key 28. When the emergency key is inserted, its beveled rear end engages the top edge 55 of the notch 53, and the roll back 29 is thereby raised to the position shown in Fig. 5, its outer end being moved 80 radially outward relatively to the key plug so that said outer end will describe a larger circle when this key is rotated than it does in the case when the change key 27 is rotated. The change key 27 is shorter than 85 the emergency key, and does not engage the notch 53; consequently, the roll back is not displaced radially by the change key, and the outer end thereof turns in a smaller circle than it does when said roll back is 90 actuated by the emergency key. When the emergency key 28 is withdrawn, the spring 49 restores the roll back to its normal position, but in some cases the spring can be omitted, because the roll back will return 95 to its normal position by gravity.

When the parts are in the position shown in Fig. 1, the latch bolt can be retracted by either of the keys 27, 28 by inserting such key and turning in a counter-clockwise 100 direction. While the emergency key turns the roll back in a larger circle than does the change key, in any event the cam will be turned into engagement with the latch retracting lever for the purpose of operating 105 the same and retracting the latch by means of the lever 33, as previously explained. On the other hand, the dead bolt 15 can only be protracted and retracted by means of the emergency key. When the change key is 110 inserted and turned in a clockwise direction with respect to Fig. 2, the roll back 29 will not reach down far enough to actuate the tumbler 16, and consequently said roll back will take up against the talon 23 nearest to 115 the face plate of the lock, and this talon will block further movement thereof, as indicated by the dotted lines in Fig. 2. The emergency key, however, will readily protract and retract the dead bolt because it 120 moves the roll bolt 29 radially outward to a position in which it will properly engage the talons, as shown in Fig. 3. The emergency key will protract the dead bolt, and then retract it, and then on continued movement of said roll back after the dead bolt has been retracted, it will abut against and operate the lever 30 of the latch mechanism and thereby retract the latch. The change key cannot operate on the latch bolt when 125 130

the dead bolt has been protracted, for it is first necessary to retract the dead bolt to bring the lever 30 into an operative position, and this can only be done by the emergency 5 key.

It will be understood that by my invention, two members of a mortise lock mechanism, for example, the members 15 and 30 may both be actuated by a single roll back, 10 such as 29, when said roll back is displaced radially relatively to the key plug by one key; whereas only one of the members, for example, the member 30, may be actuated by said roll back when it occupies its normal 15 position relatively to the key plug.

I do not claim herein the construction of the cylinder lock *per se* as the same is claimed in my application, Serial No. 191,781, filed Sept. 17, 1917.

Without limiting myself to the precise construction shown, I claim:

1. The combination with mortise lock mechanism having two movable members, of a cylinder lock having a key plug, a roll back movably mounted on said key plug, a key to displace said roll back on said key plug and operate either of said members, and a second key inoperative to displace said roll back relatively to said key plug, 25 and operable through said roll back on only one of said members; substantially as described.

2. The combination with mortise lock mechanism having two movable members located in the same plane, of a cylinder lock having a key plug, a roll back on said key plug, a key to turn said roll back in an arc of a large circle into operating engagement with either of said members, and a second 35 key to turn said rollback in the arc of a small circle into operating engagement with one of said members but inoperative on the other member; substantially as described.

3. The combination with mortise lock mechanism having two movable members located in the same plane, of a cylinder lock, a roll back on said cylinder lock, a long key to turn said roll back into operating engagement with either of said members, and a short key to turn said roll back into 45 operating engagement with one of said members but inoperative on the other member; substantially as described.

4. The combination with mortise lock mechanism having two movable members located in the same plane, of a cylinder

lock having a key plug, a roll back movable radially relatively to said key plug, a long key to turn said roll back into operating engagement with either of said members by 60 displacing said roll back radially, and a short key to turn said roll back into operating engagement with one of said members while said rollback is maintained in the initial relation to said key plug and inoperative 65 on the other member; substantially as described.

5. The combination with mortise lock mechanism having two movable members located in the same plane, of a cylinder lock 70 having a key plug, said key plug having an extension at the rear end thereof, a roll back slidably mounted on said extension to move radially relatively to the key plug, a key to displace said roll back radially and 75 move it into operating engagement with either of said members, and a second key to turn said roll back into operating engagement with one of said members while said rollback is maintained in the initial relation 80 to said key plug and inoperative on the other member; substantially as described.

6. The combination with mortise lock mechanism having two movable members, of a cylinder lock having a key plug, a roll 85 back carried by said key plug, a key for turning said key plug and roll back so as to engage the latter with either of said members depending upon the direction of rotation, and another key for turning said 90 key plug and roll back so that the latter will operatively engage one of said members but will not operatively engage the other, said roll back rotatable about the same axis by the respective keys but in different arcs; 95 substantially as described.

7. The combination with a mortise lock mechanism having two movable members, of a cylinder lock having a key plug, a roll back movably mounted on said key plug 100 and having a single operating projection, a key to displace said rollback relatively to said key plug and thereby operate both of said members by engagement therewith of said operating projection, and a second key 105 inoperative to displace said rollback relatively to said key and operable on only one of said members through said operating projection.

In witness whereof, I have hereunto set 110 my hand on the 9th day of June, 1916.

HENRY G. VOIGHT.
